UNITED STATES PATENT OFFICE.

SAMUEL H. ROADS, OF SPRINGFIELD, MASSACHUSETTS.

BOTTLE-CARRIER.

1,287,106.

Specification of Letters Patent. Patented Dec. 10, 1913.

Application filed August 5, 1912. Serial No. 243,429.

To all whom it may concern:

Be it known that I, SAMUEL H. ROADS, a citizen of the United States, and a resident of Springfield, in the county of Hampden and State of Massachusetts, have invented certain new and useful Improvements in Bottle-Carriers, of which the following is a specification.

This invention relates to a carrier for 10 bottles, and an object of the invention is to provide a handle or carrier which is simple in construction, durable and one which may be manufactured at a minimum cost.

A further object of the invention is to 15 provide a bottle carrier as specified which is particularly adapted for use in carrying a single bottle of milk, or other analogous bottles, to eliminate the liability of dropping the bottle, particularly when sending a 20 child to the store for a bottle of milk since it is well known that it is difficult for a person or child with a small hand to maintain a firm grip upon a milk bottle.

Another object of the invention is to 25 provide a bottle carrier constructed of spring steel wire including a substantially inverted U-shaped handle portion having bottle engaging stirrups formed upon the lower ends of its legs the terminals of which stirrups 30 are bent to engage over the top of a bottle neck to form a secure connection between the handle and a bottle.

Other objects of the invention will appear in the following detailed description, taken 35 in connection with the accompanying drawing, forming a part of this specification, and in which drawing:

Figure 1 is a side elevation of the device.

Fig. 2 is a perspective view of the bottle 40 carrier.

Referring more particularly to the drawing, the letter A indicates an ordinary milk bottle to which the carrier 1 is attached.

The bottle carrier 1 comprises an inverted 45 substantially U-shaped handle 2, the lower ends of the legs of which are bent to form parallel lengths 3 and 4 which extend transversely to the legs of the handle 2 and which are connected by the curved portions 5. The 50 legs of the handle 2 are preferably bent inwardly a slight distance directly upwardly of the lowermost of the parallel strands 3 as shown at 6. The parallel strands 3, are much shorter than the upper 55 strand 4, and the latter strands have their terminals bent upwardly and inwardly as

shown at 7 and 8 respectively. The upwardly bent portions 7 are provided for engaging over the bead about the mouth of the bottle A while the horizontal inwardly bent 60 portions 8 engage over the top of the mouth or bottle neck when the carrier is applied to the bottle. The upper portions 4 and the lower portions 3 are curved to snugly fit about a milk bottle and these members, which form 65 stirrups for engagement with the bottle are forced and held in bottle engaging positions by a locking or confining member 10. This member 10 is formed of a length of wire, preferably of finer gage than the wire of 70 which the handle 2 is formed and it has eyes 11 formed upon its ends which are slidably mounted upon the legs of the handle 2. The length of wire which forms the member 10 is provided with an upwardly 75 extending tongue or in other words is bent upwardly intermediate its ends as at 12 to permit a person to insert one finger beneath the member to raise it or move it upwardly along the legs of the handle 2 to allow the 80 lower ends of these legs to swing outwardly for detaching the handle from the bottle. The particular bending of the confining rod 10 also adds to the resiliency thereof and permits expansion as to length, so as to permit 85 the carrier to fit bottles of various sizes.

In order to place the carrier upon a bottle the confining wire 10 is slid upwardly along the legs of the handle 2 and the stirrups or 90 lower ends of the legs are pressed downwardly over the neck of the bottle, the ends spring apart and engage about the bottle neck. The wire 10 is now moved downwardly along the legs of the handle 2 until 95 it comes in contact with the top of the bottle which downward movement draws the stirrups firmly into engagement with the bottle neck, and securely fastens the carrier to the bottle. To remove the carrier from the 100 bottle, the confining wire 10 is pushed upwardly, thus releasing its inward pressure upon the lower stirrup ends of the handle and then a pull is administered to the 105 handle, the carrier is slipped off over the top or neck of the bottle.

Changes in details may be made without departing from the spirit of this invention, but,

I claim:

1. A bottle carrier comprising a handle 110 formed of spring wire and having its lower

portion bent to form arcuate bottle gripping stirrups, the terminals of said stirrups being bent to engage over the top of a bottle.

2. A bottle carrier comprising an inverted substantially U-shaped handle formed of spring wire and having its lower portions bent to form arcuate bottle gripping stirrups, the terminals of said stirrups being bent to engage over the top of a bottle, and 10 a confining member carried by said handle for drawing its leg portions toward each other to securely clamp said stirrups in engagement with a bottle.

3. A bottle carrier composed of spring wire bent to form an inverted substantially U-shaped handle, the lower portions of the legs of said handle each being bent to form a 15 pair of superposed parallel lengths extending transversely to the handle legs, said 20 lengths being curved to form bottle engaging stirrups.

4. A bottle carrier composed of spring wire bent to form an inverted substantially U-shaped handle, the lower portions of the 25 legs of said handle each being bent to form a pair of superposed parallel lengths extending transversely to the handle legs, the uppermost of said lengths being longer than the lower lengths and having their terminals 30 bent to engage over the top of a bottle neck.

5. A bottle carrier composed of spring wire bent to form an inverted substantially

U-shaped handle, the lower portions of the legs of said handle each being bent to form a pair of superposed parallel lengths extending transversely to the handle legs, the uppermost of said lengths being longer than the lower lengths and having their terminals bent to engage over the top of a bottle neck, 35 said lengths being curved to form bottle engaging stirrups, and a confining member 40 slidably carried by the legs of said handle for drawing the legs toward each other and to securely clamp said stirrups in engagement with a bottle.

6. A bottle carrier composed of spring wire bent to form an inverted substantially U-shaped handle, the lower portions of the legs of said handle each being bent to form a pair of superposed parallel lengths extending 50 transversely to the handle legs, the uppermost of said lengths being longer than the lower lengths and having their terminals bent to engage over the top of a bottle neck, 55 said lengths being curved to form bottle engaging stirrups, a confining member slidably carried by the legs of said handle for drawing the legs toward each other and to securely clamp said stirrups in engagement 60 with a bottle, said confining member composed of a length of wire being bent upwardly intermediate its ends.

SAMUEL H. ROADS.
